United States Patent Office.

PETER S. CRAWFORD, OF UNION, ASSIGNOR TO J. N. WHIDDEN, OF ROCKFORD, ILLINOIS.

Letters Patent No. 105,178, dated July 12, 1870; antedated June 30, 1870.

IMPROVEMENT IN THILL-COUPINGS.

The Schedule referred to in these Letters Patent and making part of the same

To all whom it may concern:

Be it known that I, PETER S. CRAWFORD, of Union, in the county of McHenry and State of Illinois, have invented a new and useful Improvement in Thill-Couplings; and I do hereby declare that the following is a full and exact description of the same, reference being had to the accompanying drawing and to the letters of reference marked thereon.

This invention relates to that class of thill-couplings which has its parts connected together without a bolt, and which parts are uncoupled by changing the usual relative positions of the axle-head and thill-iron, and consists in the specific combination of the various parts of the coupling.

In the drawing—

Figure 1 represents a plan view of the coupling complete;

Figure 2, a side elevation of the axle-head, and a plan view of the thill-iron;

Figure 3, a central longitudinal section of the coupling;

Figure 4, a transverse longitudinal section; and

Figures 5 and 6, views of different forms of rollers.

To enable others skilled in the art to make and use my invention, I will now proceed to describe fully its construction and operation.

A represents the axle-head or clip-strap, provided with the ring a, the upper part of which latter is cut away upon each side, as shown, to form the recesses a¹ a¹.

B represents the thill-iron, provided with the ears b b, having the projections b¹ b¹, as shown.

C represents a roller, provided with the depressions c c, which correspond in form and size with the projections b¹ b¹.

This roller may be provided, if desired, with the lugs b² b², as shown, but this is not essential.

The operation is as follows:

The roller C is first inserted in the eye of ring a.

If the roller is provided with lugs b² b², the eye of the ring must be formed with a beveled edge, in order to permit the roller freely to revolve. The upper part of the ring, also at a², must be cut away beneath, to permit the passage of the lug when the roller is inserted.

When thus inserted in the ring, it is turned around in the latter until its depressions are located in line below the recesses a¹ a¹.

The projections b¹ b¹ are now placed in the depressions, and the thill-iron is brought down into place. When properly constructed, the roller C should fit snugly within the eye of ring a, in order to prevent unnecessary play. The projections b¹ b¹ also should accurately fit the depressions in the roller, and the ears b b the sides of the ring a, for the same purpose.

The relative location of the recesses a¹ a¹ to the other parts of the ring is not essential. They may be so placed as to require the thill-iron to be raised to any desired height, in order to enter therein.

By this construction a simple coupling is produced, which cannot readily get out of order, and cannot become detached, except by design.

It may be constructed of any suitable material, and it may be applied to coupling-rods in steam-engines, or to any other purpose for which it is adapted.

Having thus fully described my invention,

What I claim as new, and desire to secure by Letters Patent, is—

The specific device described, consisting of the clip-strap A, with ring a, thill-iron B, with ears b b and projections b¹ b¹, and roller C, with depressions c c, the whole being combined and arranged as described, for the purpose set forth.

This specification signed and witnessed this 22d day of November, 1869.

PETER S. CRAWFORD.
